Filed Dec. 6, 1962, Ser. No. 242,770

3 Claims. (Cl. 253—39)

This invention relates to elastic fluid utilizing machines of the axial flow type, such as steam or gas turbines and air compressors, and more particularly to bladed diaphragm structure employed therewith.

Elastic fluid utilizing machines of the above type are usually provided with a casing structure divided into upper and lower halves and enclosing a bladed rotor structure and complementary bladed diaphragm structure. The diaphragm structure is also divided into upper and lower halves for ease of assembly and disassembly. During manufacture, each casing half is first fitted with the associated diaphragm halves, then the rotor is positioned in the lower casing half, and finally the upper casing half is inverted and superimposed on the lower casing half.

Since close running clearances must be established between the rotor and diaphragm structures, the placement of the diaphragm halves in their associated casing halves is critical and must be accomplished with a high degree of precision. One of the methods currently employed requires positioning each diaphragm half with respect to the central longitudinal axis of the machine. Since the longitudinal axis of the machine extends through the intersection of a central vertical plane and a central horizontal plane, in actual practice, each diaphragm half is first positioned with regard to the central horizontal plane and then positioned with regard to the central vertical plane.

This invention is concerned with an arrangement for positioning a diaphragm half in an associated casing half with regard to the central vertical plane and has for an object to provide an improved arrangement of this type.

Another object of the invention is to provide a diaphragm positioning arrangement of the above type that is readily adjustable during assembly, thereby facilitating the precise positioning of the diaphragm half and permitting larger dimensional tolerances during fabrication of the diaphragm half.

Briefly, in accordance with the invention, an annular bladed diaphragm structure is divided substantially diametrically to form a pair of substantially identical diaphragm halves of semicircular shape, each of which is provided with a semiannular array of blades carried by inner and outer semicircular ring members. The outer ring member is provided with a slotted keyway extending along a chord line disposed in spaced parallel relation to the diametric edge of the diaphragm half. A key member is slidably received in the keyway and is provided with a portion disposed normal to and projecting outwardly from the keyway and terminating beyond the periphery of the outer ring.

The inner wall of the casing half is provided with an annular groove adapted to receive the outer ring portion of the diaphragm half, and an internal bore extending partially through the casing is provided in the groove to receive the projecting portion of the key. The groove is of slightly larger radial extent than the outer ring, so that an annular clearance is attained for thermal expansion purposes during operation of the machine.

During assembly, after the diaphragm half has been placed in mating relation with the groove in the casing half and with the key projecting portion received in the bore, the diaphragm half is first vertically positioned with

2

respect to the central horizontal plane of the casing half in any suitable manner, for example, as described and claimed in R. A. Ladner application Serial No. 254,219, filed January 28, 1963, and assigned to the same assignee 5 as this invention.

Then the diaphragm half is horizontally positioned with respect to the central vertical plane, as required. This horizontal movement is freely permitted by shifting movement of the key member in the keyway. The key member is then locked in its final position by any suitable means.

The above and the objects are effected by the invention, as will be apparent from the following description and claims taken in connection with the accompanying drawings, forming a part of this application, in which:

FIGURE 1 is a cross-sectional view of a steam turbine having the invention incorporated therein;

FIG. 2 is a central vertical sectional view taken on line II—II of FIG. 1, but with the rotor omitted for clarity;

FIG. 3 is an enlarged fragmentary view taken on line III—III of FIG. 1;

FIG. 4 is a fragmentary view taken substantially on line IV—IV of FIG. 3, but with the locking means provided at final assembly;

FIG. 5 is a fragmentary view taken on line V—V of FIG. 4 and looking upwardly; and

FIGS. 6 and 7 are respective side elevation and bottom views of a keying member employed with the invention.

Referring to the drawings in detail, in FIG. 1 there is shown an axial flow, multi-stage steam turbine 10 having a tubular casing or shell structure, of substantially circular internal cross-sectional shape, divided into an upper half portion 11 and a lower half portion 12 along 35 a central horizontal plane extending through the longitudinal axis of the casing structure, and joined at suitable flanges by suitable bolts 13. Within the upper and lower halves 11 and 12, there is rotatably supported a rotor 14 having a plurality of annular rows of blades (not shown). 40 As well known in the art, the turbine may be provided with a plurality of expansion stages, as desired. Each of the stages is divided by a bladed diaphragm structure 15 received within the casing structure 11, 12. As illustrated in FIG. 2, the steam turbine contains four diaphragm structures, and thus is divided into four stages.

The diaphragm structures 15 are of annular shape and include an outer ring structure 16, an inner ring structure 17 disposed concentrically with the outer ring structure 16 about a central axis, and an annular array 50 of nozzle blades 18 disposed therebetween, as well known in the art.

For ease of manufacture and assembly, the diaphragm structures 15 are each diametrically divided into an upper half portion 19 and lower half portion 20, thereby 55 imparting a semicircular shape to each of the diaphragm halves. This is attained by splitting the outer and inner ring structures 16 and 17, respectively, into semicircular halves or portions.

The inner diaphragm ring 17 may further be provided 60 with a divided labyrinth seal ring structure 21 disposed in concentric but closely spaced relation with the rotor 14, thereby permitting rotation of the rotor but minimizing leakage of steam therewith from stage to stage. Accordingly, as shown in FIG. 1, there is provided an annular space 22 of very small width between the labyrinth ring 21 and the rotor 14. Since the space 22 is of relatively small width, it is essential to position the rotor 14 in closely controlled concentric relation with the diaphragm structures 15.

As illustrated in FIG. 1, the upper and lower diaphragm halves 19 and 20 are disposed in mutual abutment at their diametric edges 23 and 24, respectively,

and maintained in keyed relation with each other by a pair of suitable keys 25, as well known in the art.

During assembly of the diaphragms 15 and the rotor structure 14 in the casing, the lower casing half 12 is disposed as illustrated in FIG. 1, that is with its longitudinal central axis disposed in a horizontal plane. The diaphragm halves 20, corresponding to the lower casing half 12, are then positioned in the lower casing half 12, in such a manner that their central axes are substantially coincident with the central axis of the casing structure.

To precisely space and position the diaphragms 15 along the longitudinal axis of the casing structure 11, 12, the upper and lower halves of the casing structure are provided with annular grooves 26 disposed in axially spaced relation with each other and parallel to a plane normal to the axis of the casing structure.

To permit thermal expansion of the diaphragms 15 within the casing 11, 12 during operation, the diaphragms 15 are formed to a slightly smaller radial dimension than that of the grooves 26, thereby permitting the employment of an annular space 27 of small width between each of the diaphragm outer rings 16 and the inner surfaces of the associated grooves 26, as best shown in FIGS. 3 and 4. Accordingly, to maintain the diaphragms 15 in centered relation with the turbine casing structure 11, 12, the diaphragms must be supported against vertical movement in downward direction as well as horizontal movement. In actual practice, the upper and lower diaphragm halves 19 and 20 are positioned with respect to the horizontal central plane by suitable means beyond the scope of this invention. However, one of such means for supporting the diaphragm halves in this manner is described and claimed in R. A. Ladner application Serial No. 254,219, filed January 28, 1963, and assigned to the same assignee as this invention.

In accordance with the invention, each of the grooves 26 in the casing portions 11 and 12 is provided with an internal bore 28 disposed in the wall of the casing and extending in radially outwardly direction to a limited extent. This bore 28 is preferably disposed with its central axis in a vertical central plane bisecting the lower casing half 12 (see FIG. 2).

Since the invention may be applied to the upper and the lower diaphragm halves in a substantially identical manner, only one of the lower diaphragm halves 20 will be described. The lower diaphragm half 20 corresponding to the lower casing half 12 is provided with an elongated keyway 29, which keyway may be of T-shaped cross-section (as best shown in FIGS. 2 and 3). The keyway 29 extends in a chordwise manner along a chord line disposed in parallel relation with the diametric edge 24 of the lower diaphragm half 20 or, stated in another manner, it is disposed normal to and extends in opposite directions from a vertical central plane bisecting the lower diaphragm half 20.

A key member 30, preferably of T-shape, is slidably received in the keyway 29 and is provided with a flange portion 31 held captive in the keyway and a projecting portion 32 extending outwardly therefrom. The projection 32, as best shown in FIGS. 5 and 7, is desirably of square cross-section. The bore 28, on the other hand, may be of elongated oblong shape. However, the bore 28 is of elongated shape in a direction parallel to the central longitudinal axis of the casing, so that the key projection 32 is free to move therein in a direction parallel to this axis. However, in a direction normal to the axis of the casing, the projection 32 fits snugly in the bore 28, so that only a very small amount of play, in this direction, is attained. The outer ring 16 may further be provided with a threaded opening 33 extending into the keyway 29 (as best shown in FIG. 3). A suitable set screw 34 is threadedly received in the threaded opening 33 for a purpose which will subsequently be described.

During assembly, the lower half of the casing 12 is disposed in the position shown in FIG. 1 and the lower diaphragm half 20, with the key 30 fitted in the keyway 29, is lowered into mating relation with the associated groove 26. At this time, the key 30 is preliminarily positioned in such a manner that its projection 32 is received in the bore 28, while the set screw 34 is disposed out of locking engagement with the key 30. Accordingly, the lower diaphragm half 20 is freely movable, relative to the casing half 12 in a horizontal direction, normal to the central vertical plane. The lower diaphragm half 20 is then adjustably positioned until the spacing 27 between the periphery of the lower diaphragm half 20 and the groove 26 is substantially uniform throughout its extent. After this position is attained, the set screw 34 is screwed downwardly into tightly fitting engagement with the flange portion 31 of the key, thereby ensuring that the key 30 will not inadvertently or otherwise be moved out of the position thus attained.

Subsequent thereto, the lower diaphragm half 20 may be removed from the lower casing half 12 and, if desired, the key 30 may be more firmly and positively locked in the keyway 29 by a pair of pins 35 (see FIGS. 4 and 5). These pins 35 may be of the dowel type and driven into tight engagement with a pair of holes 36 drilled in the diaphragm ring 20. To facilitate the drilling of the holes 36, the key 30 may be originally provided with a pair of holes 37 to permit location of the holes 36. With the key 30 thus firmly locked in its final position, the set screw 34 may be removed, if desired, and the lower diaphragm half 20 is then refitted to the lower casing half 12.

In the same manner, all of the other diaphragm halves 19 and 20 may be positioned in the lower and upper casing halves 11 and 12, respectively.

Accordingly, with the lower half of the casing 12 and lower diaphragm halves 20 in properly assembled relation, the rotor 14 may then be lowered into position, and, subsequent thereto, the upper casing half 11 with its upper diaphragm halves 19 in proper assembly relation may be superimposed on the lower casing half 12, and the entire structure joined by the bolts 13 to complete the assembly. Upon final assembly of the apparatus as described above, the annular clearance space 22 between the rotor and the seal rings 21 is assured of being substantially uniform in width, thereby minimizing the possibility of eccentricity between the rotor 14 and the seal rings 21 with otherwise attendant excess leakage of steam and/or rubbing between the seal rings and the rotor.

With the above arrangement, even though during manufacturing close dimensional tolerances in machining may not be attained, the adjustable keying arrangement provided by the keyway 29 and the key 30 serves to overcome such variations in manufacture and permit precise positioning of the diaphragm structure 15 in the casing structure.

While the invention has been shown in one form, it will be obvious to those skilled in the art that it is not so limited, but is susceptible of various other changes and modifications without departing from the spirit thereof.

We claim as our invention:

1. An axial-flow elastic fluid utilizing machine comprising
  - a tubular casing structure having a first central axis and having an internal wall portion of substantially circular cross-sectional shape concentric with said axis,
  - said casing structure being axially divided along a central horizontal plane into upper and lower casing half portions,
  - an annular diaphragm structure disposed in said casing structure and having a second central axis,
  - said diaphragm structure being diametrically divided

into upper and lower diaphragm half portions of substantially semicircular cross-sectional shape, said upper and lower diaphragm half portions being associated with said upper and lower casing portions, respectively,

one of said diaphragm half portions having a semicircular outer ring portion disposed adjacent the internal wall of the associated casing portion, the associated casing portion having a bore in its internal wall,

10 said ring having an elongated keyway extending chordwise therethrough,

a key member received in said keyway and slideable chordwise therein and having a portion projecting outwardly from said keyway into engagement with

5

15

said bore, and means carried by said ring portion for locking said key to said ring portion.

2. The structure recited in claim 1 in which the one diaphragm half portion is of smaller radial extent than 20 the wall portion of the associated casing half portion, and

said key member is effective to maintain the second central axis in a vertical plane extending through the first central axis.

25

3. The structure recited in claim 1 in which the keyway extends along a chord line disposed substantially parallel to the horizontal plane, and

said key member is effective to maintain the second central axis in a vertical plane extending through 30 the first central axis.

4. An axial-flow elastic fluid utilizing machine comprising

a tubular casing structure axially divided into first and second casing half portions of substantially semicircular internal cross-sectional shape,

35

an annular diaphragm structure received in said casing and diametrically divided into first and second diaphragm half portions of substantially semicircular cross-sectional shape,

said first and second diaphragm half portions being received in said first and second casing half portions, respectively,

said first casing half having a semicircular groove and an internal bore communicating with said groove,

40

45 said first diaphragm half having a semicircular outer ring portion received in said groove,

said ring portion being of smaller radial extent than said groove,

said ring portion having an elongated keyway extending chordwise therethrough, a key member slidably received in said keyway and slideable chordwise therein, said key member having a portion projecting transversely and outwardly from said keyway,

said projecting portion being disposed in mating relation with said bore and positioning said first diaphragm half in said first casing half, and means for locking said key to said ring portion.

5. The structure recited in claim 4 in which said first and second diaphragm half portions have diametrically extending edges disposed in abutment with each other, and

said keyway extends along a chord line disposed substantially parallel to said edges.

6. The structure recited in claim 4 in which said keyway is disposed normal to a central plane bisecting said first diaphragm half, and

said key member is effective to prevent movement of said first diaphragm half in a direction normal to said central plane.

7. The structure recited in claim 1 in which the bore and the key member are so proportioned relative to each other that the key member is freely movable therein in a direction parallel to the central axis of the casing but restrained by the bore from horizontal movement transverse to the central axis.

8. The structure recited in claim 4 in which the bore is elongated in a direction parallel to the central axis of the casing structure, and the key member is so proportioned with relation to the bore that the former is freely movable therein in said direction but restrained by the bore from movement transverse to said direction.
